HYDROCARBON-FUEL BURNER.

1,292,258.

Specification of Letters Patent. Patented Jan. 21, 1919.

Application filed November 8, 1917. Serial No. 200,940.

To all whom it may concern:

Be it known that we, ALLEN W. CLARKE and LEE M. CARL, residing at Jeffersonville, Indiana, and being citizens of the United States, have invented certain new and useful Improvements in Hydrocarbon-Fuel Burners, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Figure 1 is a plan view of the improved hydrocarbon fuel burner showing a short section of supply pipe leading thereto; and Fig. 2 is a vertical section thereof taken on the line 2—2 of Fig. 1.

This invention relates to burners for hydrocarbon fuels in which there is a generating chamber for the conversion of liquid fuel into gas, the chamber forming shell being supported by the upper end portion of an outlet conduit from the chamber. Such conduit serves as a standard for supporting the chambered generator and extends upwardly from a base with which it is rigidly combined.

This base is in the form of a receptacle for liquid fuel adapted to preheat the generating chamber, which is spaced above and over the base. Liquid fuel may be poured directly into the base-forming preheating receptacle, but provision is made for feeding fuel into the generating chamber from which it may flow through the standard-like outlet conduit to escape therefrom into the preheating receptacle to be, if desired, received by suitable absorbent material. The orifice from which the liquid fuel escapes into the preheating receptacle is positioned under the generating chamber at a predetermined distance, whereby certain advantageous results are obtained. After the liquid fuel initially introduced into the base-like receptacle is ignited and has preheated the generating chamber, the fuel fed into the chamber will vaporize and pass down the standard-forming conduit into the base-like

receptacle to escape from the lower conduit orifice that is spaced with particularity below the generating chamber.

In consequence of the relation of this orifice to the generating chamber, the gas will 60 not burn until it reaches the zone directly under the generator, the distance between the orifice and this zone being sufficient to permit a proper mixture of air with the gas.

Another object is to provide the generating chamber with a top outlet which promotes a steady flow of the fuel, prevents liquid fuel from accompanying the gasified fuel into the outlet conduit from the chamber after the preheating has been completed, 70 and which also tends to prevent foreign particles from passing into the outlet conduit that leads to the burner orifice.

Other features becoming apparent hereinafter are also to be regarded as coming 75 within the scope of the present invention.

Referring to the drawings, 1 indicates a preheating pan or receptacle and 2 a pipe or tubular standard extending upwardly therefrom. The upper and lower portions 80 of pipe 2 are bent to be disposed horizontally, the lower horizontal portion of pipe 2 lying on the bottom wall of preheating pan 1 and being welded thereto as at *x*. After being bent upwardly, the lower portion of 85 pipe 2 is further welded to the vertical wall of preheating pan 1, as at *y*.

The upper horizontally bent portion of pipe 2 extends to a position over preheating pan 1 and is shown as having its upper 90 terminal threaded. Screwed or otherwise affixed to the terminal of the upper horizontally disposed portion of pipe 2, is a gas generator 3 provided with a top outlet 4 into which the upper end of pipe 2 is introduced, and there connected.

The gas generator, in the embodiment being described, is disk-like and is formed of spaced plates and an annular ring unitarily joined together. One of the plates 3^a is flat 100 and forms the bottom wall, while the top wall is formed by the other plate 3^b, and the vertical or side wall by the ring 3^c. The spacing of the top and bottom plates by the ring forms a chamber 5, which is the main 105 or vaporizing chamber.

The top outlet 4, as shown, has the general appearance of an elbow pipe fitting and being hollow provides a chamber 4^a therein. The outlet 4 is integral with the top plate 110

3^b and the chamber 4^a therein is in communication with the chamber 5 and is provided in one side wall with a threaded opening adapted to receive and cooperate with the 5 other end of the conduit 2. The chamber 4^a may thus serve as a collecting and condensing chamber as will be more apparent hereafter.

It is preferred to make the gas generator 10 3 and the outlet 4 as a unitary structure. In order that fuel may be fed into the chamber 5, the ring or vertical wall 3^c is provided with a threaded opening 6, and concentric with the opening is a boss 7 that serves to 15 strengthen the wall and at the same time provide for a greater length of threads.

Screwed into threaded aperture 6 of the generating chamber 5, is a bushing 8 having an outer hexagonal head, which bushing 20 is provided with an internal passage. Into the end of this passage in bushing 8 which opens into generating chamber 5, is projected a pipe 9 that is secured to bushing 8 preferably by welding it therewith at 2.

25 For an appropriate distance inwardly from the headed end of bushing 8, the passage through that bushing is threaded to receive the end of a supply pipe 10. Supply pipe 10 leads in suitable manner to a supply 30 tank 11 adapted to contain hydrocarbon fuel, and is provided, intermediate the tank 11 and the generating chamber 5, with a control valve 12.

Desiring to use the hydrocarbon burner, 35 liquid fuel is first introduced into preheating pan 1 where it will be retained by suitable material, such as the asbestos sheet 13. This liquid fuel may be directly poured into pan 1 or valve 12 may be opened. When 40 the latter method is employed, hydrocarbon fuel will flow through supply pipe 10 and pipe 9 to be discharged into generating chamber 5 of the gas generator 3. Pipe 9 projects from the inlet of the generating 45 chamber 5 to extend past the top outlet 4 and close to the opposite side of the generating chamber, thereby preventing the oil from immediately passing into pipe 2, the discharge end of pipe 9 being beveled to 50 create an overhanging shield 14 which further contributes to this end.

As the hydrocarbon fuel continues to flow 55 into generating chamber 5, it rises in top outlet 4, thereafter escaping through the upper end of pipe 2 to pass down that pipe into its lower horizontal portion that is located in the bottom of preheating pan 1. Through the upper side of the wall of the lower horizontal portion of pipe 2 is an outlet 60 let orifice 15 through which the liquid fuel escapes into the preheating pan, the adjacent end of pipe 2 being sealed by welding the wall of the pipe, or by inserting a plug into the end of the pipe and welding it to 65 the wall, as at w.

A suitable amount of liquid fuel having been admitted to preheating pan 1, valve 12 may be closed and the fuel ignited, the resulting flame preheating generating chamber 5 and converting the liquid fuel therein into gas. As the liquid fuel initially admitted to preheating pan 1 is consumed, the gas now developed in generating chamber 5 will pass through pipe 2, and, after that pipe has become free of liquid fuel, this gas will escape through orifice 15 and flow toward the under side of generating chamber 5.

It has been found by experience that certain advantageous results can be obtained by accurately spacing orifice 15 below the bottom wall of the gas generating chamber 5. In a device of the proportions illustrated, by spacing orifice 15 three and one-half inches below the bottom wall 3^a of chamber 5 will give excellent results. With the orifice so spaced below generating chamber 5, the gas issuing from orifice 15 will burn in practical operation directly under the bottom wall of generating chamber 5, and the space between orifice 15 and that zone is sufficient to allow 9₁ such a mixture of air with the issuing gas that a blue flame, indicating substantially perfect combustion, will result. As the bottom wall 3^a of the chamber 5 is the lower flat end of a cylindrical body, the flame in impinging against it will spread, the flat surface assisting in preserving the blue flame.

The outlet 4 of the gas generator is adapted to serve as a dome in which under service conditions the liquid fuel does not rise to 10 escape through pipe 2. Except for the presence of pipe 9 and hydrocarbon fuel, generating chamber 5 is unoccupied, save as for such foreign particles as may enter this chamber. Because of the positioning of top 10 outlet 4, these foreign particles are unable to rise to pipe 2 during the operation of the burner and enter it. As the chamber 4^a is arranged or superposed above the chamber 5, it will serve to collect the gas. Should any 11 of the fuel remain liquid and pass into the chamber 4^a it will condense on the wall thereof and drip onto the hot bottom wall 3^a.

The burner is compact and such parts of it as require little or no attention are rigidly 11₁ united, but provision is made whereby the casting constituting the gas generator may be removed and cleaned. To accomplish this, supply pipe 10 may be disconnected from bushing 8, and said bushing may be 120 screwed out of orifice 6. With the removal of the bushing, pipe 9, which is welded or otherwise secured to it, is withdrawn and the gas generating chamber 5 may be 125 screwed off the upper horizontally disposed end of pipe 2. By suitable washing or with the use of a blast, the interior of the gas generator 3 may be thoroughly cleansed, after which the parts may be assembled as shown in the drawings.

What we claim is:

1. A gas generator for hydrocarbon fuels comprising a hollow disk-like member formed with a smooth-walled single clear chamber having a threaded inlet port in one side thereof and provided with a unitary superposed chamber having one of its lateral walls provided with a threaded outlet port. 5
2. A burner for hydrocarbon fuel comprising a receptacle for preheating fuel forming a cup-like base, a conduit having a closed end lower portion bent and unitarily secured in the receptacle, said lower portion having an orifice near said closed end, said conduit 10 extending upwardly from the receptacle and having a bent upper portion provided with a threaded open end, a gas generator composed of superposed clear chambers, each of said chambers being provided with a threaded port in a side wall, the port in the upper chamber being connected with the threaded open end of the conduit, and a bushed and removable pipe adapted for connection with the threaded port in the lower chamber to 15 extend thereacross to discharge fuel near the opposite side of said chamber. 20
3. A burner for hydrocarbon fuel comprising a pan-like receptacle for preheating fuel, a conduit secured therein to extend upwardly therefrom and having upper open end and lower closed end portions laterally deflected, there being an outlet orifice formed in said lower deflected portion, a gas generator provided with superposed communicating 30 chambers connected with and supported by the deflected conduit portion over and above said orifice and in communication therewith through said conduit, and a pipe extending within the gas generator adapted to discharge liquid fuel into the gas generator chamber. 35
4. In combination in a burner for hydrocarbon fuel, a pan-like receptacle for preheating fuel, a single chambered gas generator spaced vertically above the same and having a collecting chamber thereon, which latter chamber is provided with a side outlet, a conduit having a closed end lower portion rigidly unified with and disposed in 40 said receptacle to extend along the bottom thereof and upwardly therefrom for connection with said outlet, there being an outlet orifice in the lower part of said conduit directed upward toward the bottom of said gas 45 generator, and a unified bushed and detachable pipe having an obliquely cut open end and adapted to supply liquid fuel to the gas generator chamber. 50
5. In combination in a burner for hydrocarbon fuel, a receptacle for preheating fuel, a conduit entering and extending above and over the same, a gas generator supported thereby and having a single clear chamber therein and an inlet therefor, said 55 chamber and inlet both being positioned be- 60
- low the upper end of said conduit, the upper wall of said chamber having a chambered top outlet thereon from which the conduit leads to an orifice therein below the bottom wall of said chamber, a discharge pipe rigid 70 with the wall of said chamber extending diametrically thereacross from its inlet to adjacent the opposite side of the chamber, and a pipe adapted to convey liquid fuel to said discharge pipe. 75
6. In combination in a burner for hydrocarbon fuel, a receptacle for preheating fluid, a gas generator spaced thereabove having a chamber provided with an inlet and an outlet located, respectively, at the side 80 and top of said chamber, a bushing held in said inlet, a discharge pipe unified with said bushing and projecting below said outlet into proximity to the opposite side of said chamber, a liquid fuel supply pipe connected 85 to said bushing, and a conduit having an upper end supporting said generator from said receptacle and having an outlet in its lower portion under the generator chamber. 90
7. In combination in a burner for hydrocarbon fuel, a gas generator having an unobstructed chamber the bottom wall of which is flat, said chamber having a top outlet, a pipe extending transversely of the chamber and adapted to discharge liquid 95 fuel into said chamber, and a conduit leading from said chamber top outlet to an outlet orifice in the lower portion of the conduit, said orifice being predeterminedly positioned below the flat bottom chamber wall 100 and cooperating therewith so that gas issuing from said orifice will mix with air without igniting until in proximity to said chamber bottom wall, and there burning with a substantially blue flame. 105
8. In combination in a burner for hydrocarbon fuel, a gas generator comprising an unobstructed main chamber portion having a flat bottom wall, a top wall and a side wall containing an inlet aperture, the top 110 wall having a dome-like portion projecting above its normal upper surface and containing an outlet aperture, and a removable discharge pipe adapted to project into and partly across said chamber, said pipe being 115 unified with a bushing to permit said pipe to be removably positioned in said inlet aperture and to be connected to a fuel supply pipe. 120
9. In combination in a burner for hydrocarbon fuel, a gas generator comprising a main chamber portion having a flat bottom wall, a top wall and a side wall containing an inlet aperture, the top wall having a chambered dome-like portion thereon to project 125 above its normal upper surface and provided with an outlet aperture, and a removable discharge pipe projecting horizontally into and partly across said chamber, said pipe being unified with a bushing adapted to be 130

removably positioned in said inlet aperture and to be connected to a fuel supply pipe.

10. In combination in a burner for hydrocarbon fuel, a receptacle for receiving preheating fuel, a conduit having near one of its ends a fuel discharge opening for and in the receptacle and connected thereto, a hollow disk-like gas generator provided on its upper wall with a chamber having an outlet in a side wall thereof for connection with the conduit, said generator having in its side wall a threaded inlet opening, a bushed inlet pipe adapted to coöperate with said latter opening to project therethrough 15 within and horizontally across the gas generator so that its free end terminates near the side opposite the threaded opening, and a pipe adapted to convey liquid fuel from a source of supply to the bushed inlet pipe.
20. 11. A gas generator for hydrocarbon fuels comprising a hollow disk-like member having a threaded inlet port in a side wall thereof and provided on its upper side with a unitarily joined chamber having in one of its lateral walls a threaded outlet port, and a unified bushed inlet pipe for engaging with the inlet port and projecting within and across the disk-like member to terminate near the wall on the side opposite the 25 threaded inlet port.

12. A gas generator for hydrocarbon fuels comprising a hollow disk-like member having a single, clear chamber therein and provided with a threaded inlet port, the central portion of the upper wall of said member being dome-like to form a chamber having communication with the first chamber, said central portion having a vertical wall provided with a threaded outlet port.

40. 13. As a new article of manufacture, a gas generator comprising a hollow disk-like casting having a single clear chamber and provided with a threaded inlet port in a side wall thereof with the center portion of its top wall projected therefrom to form a chamber therein for communication with the first chamber and having a threaded outlet port in a side wall thereof, said ports being directed oppositely to each other in horizontally parallel planes.

50. 14. As a new article of manufacture, a gas generator formed of a hollow disk-like unitary casting producing a clear smooth walled main chamber therein with a collecting chamber superposed thereon having communication with the main chamber, each of said chambers having a threaded port to co-operate with a pipe.

60. 15. A burner for hydrocarbon fuels comprising a pan-like receptacle for preheating fuel and forming a base, a U-shaped conduit having one of its limbs secured to and in the receptacle so that the transverse portion of the U extends upwardly therefrom, said limb having a perforation near its outer

and closed end serving as fuel-opening, a gas generator composed of a single chamber forming member having a threaded outlet port in a side wall, a dome-like projection on and formed by the upper wall of said generator inclosing a chamber having communication with the first chamber, said projection including a vertical wall having a threaded outlet port to coöperate with the other limb of the conduit, a removable bushing to coöperate with the threaded port in the side wall of the first chamber and having unified therewith an inlet pipe adapted to extend across the chamber with its end disposed adjacent the opposite wall of said chamber, and a pipe connected with the bushing to supply fuel to said chamber and conduit.

16. A burner for hydrocarbon fuel comprising a circular walled open top cup for receiving preheating fuel, a conduit having a bent lower portion unified with a side wall and the bottom of the cup, the outer end of said conduit being closed and having an orifice formed in the wall of the conduit, the upper end of the conduit being also bent to lie in a plane parallel to lower portion, said upper portion being of less length than the lower portion, a gas generator composed of superposed communicating chambers, each of said chambers being formed free of obstructions and provided with threaded ports, the upper one of said chambers being connected to the upper end of the conduit for supporting the generator, a bushing having an outlet pipe unified therewith for connection with the port in the lower chamber and to extend thereacross with its free end angularly directed toward the bottom thereof, said generator being substantially circular in outline and of lesser diameter than the preheating fuel cup.

17. A burner for hydrocarbon fuel comprising a gas generator composed of a main generating chamber and a communicating superposed gas collecting chamber, each of said chambers being provided in a side wall with a threaded port, a receptacle below said generator adapted to receive preheating fuel, a continuous length conduit having a lower portion provided with a closed end and with an orifice near said end, said portion being unified with the bottom and a side wall of the receptacle, the end of the upper portion being open and threaded for connection with the gas collecting chamber, a bushing to coöperate with the threaded port of the gas generating chamber, a discharge pipe unified with the bushing and adapted to project across said latter chamber on one diameter thereof to discharge fuel onto the bottom wall of the generator adjacent a side wall, and a fuel supply pipe adapted to be connected to the bushing.

18. A burner for hydrocarbon fuel com-

prising an open cup-like receptacle for retaining preheating fuel, a conduit having a closed end bent lower portion secured in the receptacle to a side wall and a bottom wall and provided with an orifice near the closed end, said conduit extending vertically upward from the side wall and having a bent upper portion provided with a threaded and open end, a hollow disk-like gas generator 10 formed with a single clear chamber in the body thereof and a collecting chamber formed by an outwardly projecting portion of the top wall, each of said chambers having a threaded port in a side wall, the port 15 in the collecting chamber being connected with threaded open end of the conduit which

serves as a support for the generator, a bushing to coöperate with the other port, an open-ended pipe unified with the bushing to project diametrically across the clear 20 chamber for discharging fuel near the opposite side of the chamber, said bushing being adapted to be connected with a fuel supply.

In witness whereof we have hereunto set 25 our hands in the presence of two witnesses.
